OFFSET PRINTING DEVICE

John McK. Ballou, Pasadena, and Oscar C. Fil-
liung, Los Angeles, Calif., assignors to Kirk-
Rich Dial Corp., Los Angeles, Calif., a corpora-
tion of California

Application August 26, 1946, Serial No. 693,088

7 Claims. (Cl. 101—41)

1

This invention relates to offset printing and deals more particularly with a machine for printing watch dials and the like.

The primary object of the present invention is to provide a simple relatively inexpensive yet accurate machine for printing the faces of watch dials either in their entirety or to add thereon imprints such as names, trade-marks and other indicia.

Another object of the invention is to provide novel means for registering the offset printing positions of both a printing plate and a dial for receiving an imprint therefrom whereby an accurate printing operation is quickly and easily performed.

Another object of the invention is to provide novel mounting and holding means for the printing plate and the watch dial and to embody effective means whereby said plate and dial are accurately relatively registered by adjusting said means for accurate printing of the latter by transfer of ink from the former.

A further object of the invention is to provide a novel support for the dial and a similar support for the printing plate and to provide means for adjusting said supports from approximate to accurately registered relative positions.

A further object of the invention is to provide a watch dial printer as indicated embodying a horizontally and angularly adjustable bed which mounts the printing plate and dial and further includes a vertically reciprocative tympan for effecting transfer of ink from the printing plate to the dial.

A still further object of the invention is to provide detent means for the mentioned bed releasable upon reverse manual movement of the means employed for operatively moving the tympan.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

2

Fig. 1 is a top plan view of a watch dial printer according to the present invention.

Fig. 2 is a vertical sectional view as taken on the line 2—2 of Fig. 1.

5 Fig. 3 is a fragmentary side elevational view of the upper portion of the printer.

Fig. 4 is a plan sectional view as taken on line 4—4 of Fig. 2, the horizontally swingable bed being shown in another position.

10 Fig. 5 is a broken sectional view as taken on line 5—5 of Fig. 1.

Fig. 6 is a similar sectional view taken through the center of the dial mounting means shown in Fig. 5.

15 Fig. 7 is a broken plan view as taken on line 7—7 of Fig. 6.

Fig. 8 is a broken plan view of the printing plate mounting means.

Fig. 9 is a side view thereof.

20 Fig. 10 is an enlarged cross-sectional view as taken on line 10—10 of Fig. 5.

Fig. 11 is a fragmentary and enlarged vertical sectional detail view of the printing plate mounting means.

25 Fig. 12 is an enlarged broken sectional view as taken on line 12—12 of Fig. 3.

The machine which is illustrated is intended primarily as a watch dial printer although printing of other articles may be accomplished thereby. In its present form, the printer comprises, generally, a base 15, a standard post 16 mounted vertically thereon, a horizontally and radially adjustable bed 17 adjacent to the base 15, anti-friction means 18 mounting said bed for

30 movement on the post 16, printing plate mounting means 19 and watch dial mounting means 20 on the bed 17, a head 21 carried by the upper end of the post 16, vertically reciprocative means 22 carried by the head for movement toward and from the bed 17 and mounting on ink transferring tympan 23, handle means 24 for

35 moving the means 22, detent means 25 carried by the head 21 and selectively engageable with the bed 17 for locating the latter in adjusted position, means 26 coupled with the handle means 24 for releasing the detent means 25, a

40 guide member 27 for said means 25, and a vertically adjustable reticle means 28 carried by the member 27 and associated, selectively, with the means 19 and 20 to provide visual aid in accurately positioning the printing plate P and watch dial D mounted on said means 19 and 20, respectively.

The base 15 is a generally rectangular plate 29 formed with a boss 30 for receiving the lower

reduced end 31 of the standard post 16 and with suitably disposed bosses 32 whereby the base may be secured on a support.

The means 18 is mounted on said reduced end 31 of the post 16 and comprises a pair of anti-friction bearings 33, one against the boss 30 of the base and one against the shoulder 34 formed by the reduced end 31. A spacer 35 is provided between the bearings 33, and a nut 36, on the under side of the base, serves to lock the post rigidly on the base by drawing the shoulder 34 down on the upper portion of the bearings 33. The inner races of the bearings 33 are thus held against rotation, leaving the outer races free to revolve. The bed 17 is mounted on said outer races and thus may be horizontally moved about the post 16.

The bed 17 is formed as a casting of generally triangular form. Said bed has a boss 37 at one apex for the bearings 33, a circular opening 38 at another apex, and a generally oval opening 39 at the third apex. The openings 38 and 39 are of such size as to permit relative adjustment of the respective mounting means 19 and 20 with the center of the post 16 and with each other.

The means 19 comprises a block 40 on the bed, a stem 41 on the block extending through the oval opening 39, and a plate 42 fixed on the stem by a nut 43 and against the under face of the bed. The stem 41 is of such length with relation to the thickness of the bed as to permit movement of the block 40 along the upper face of the bed as limited by the opening 39. A pair of spring-urged pins 44, carried by the bed, are arranged to press downward on the upper face of plate 42 and thereby create a friction between the block 40 and bed 17 of sufficient magnitude to fix the block against movement. A fork 45, having its tines 46 apertured for the pins 44, is bent to provide a fulcrum 47 which acts on a plate 48 that is fixed to and forms part of the bed. Said fork is provided with a handle 49 extending through a radial slot 50 in said bed. The plate 48 is formed with a similar projecting handle 51. By grasping the handles 49 and 51 and depressing the former, the fork 45 is tilted on its fulcrum 47 to cause lifting of the pins 44. Since the mentioned friction between the block 40 and bed 17 is now eased, the block may be readily shifted as limited by the opening 39. Upon release of the handles 49 and 51, the mentioned friction becomes effective to lock the block 40 in adjusted position. Suitable undercut pins 91 are provided on the upper face of block 40 to locate plate P thereon. A spring-tensioned lever 92, pivoted on the block, is so associated with said pins that the same engages an edge of plate P to press said plate into firm engagement with the pins.

The means 20 is substantially similar to the means 19, and the parts thereof, therefore being given similar reference numbers. The only differences in the structures are the openings 39 and 38 and the blocks 40 and 52 for the means 19 and 20, respectively.

The block 40 is designed to receive and hold the printing plate P which is generally larger than a watch dial and frequently bears several intaglio engravings for selective use. Accordingly, the oval opening 39 permits of a greater range of adjustment of block 40, so that a selected engraving may be properly placed in registered position. The block 52 is generally cup-shaped and is filled with a quantity of beeswax 53 in

which a watch dial D is adapted to be embedded as best seen in Figs. 4 and 5.

The head 21 comprises a casting 54 mounted by clamp bolts 55 on the upper portion of the standard post 16. The casting extends radially and may be locked in any desired position with respect to the base 15. The outer end of the head carries a spaced pair of rollers 56 which preferably are anti-friction bearings arranged to guide the vertical movement of the reciprocative means 22. The latter means consists of a bar 57 formed with longitudinal grooves 58 in which the rollers 56 are engaged. Mounted in this manner, the bar 57 is movable, with a minimum lateral play, toward and from the bed 17. A bottom plate 59 on the bar forms a stop to limit the upward movement thereof and a top plate 60 serves to limit the downward movement of said bar with respect to the head 21. A tension spring 61 normally holds the bar 57 in elevated position with the stop 59 against the lower face of the head. The tympan 23 extends downwardly from the bar 57 and comprises a gelatinous mass capable of receiving ink from the intaglio engravings in the plate P and imprinting the same on the dial D.

The handle means 24 comprises a handle 62 on a bail or yoke 63 mounted on pivot screws 64 in the head 21, a pair of links 65, a pivotal connecting screw 66 in plate 60 for the upper end of each link, and a connecting screw 67 in the handle bail 63 for the lower end of each link. Depressing of the handle 62 will cause the same to pull on the links 65 and the latter will depress the bar 57 against the pull of the spring 61. Release of the handle will cause the spring 61 to be effective for raising the bar.

The detent means 25 comprises a rod 68 which projects into a clearance seat 69 in the head 21, a collar 70 on said rod which serves to confine a compression spring 71 in said seat, and selective seats 72, 73 and 74 formed in the upper surface of the bed 17 and receptive of the lower end of said rod.

The means 26 consists of a forked arm 75 engaged about the rod 68 and positioned beneath the collar 70, a pivot 76 for said arm on the head 21, a transverse bar 77 on the handle bail 63 engaged with an intermediate portion of the arm 75, and a slot 78 in the lower end of each link 65 through which the screws 67 extend. The spring 71 normally depresses the rod 68 into that seat 72, 73 or 74 which is in register therewith. Whereas, a downward movement of the handle 62, causes a downward movement of the bar 57 and of the tympan 23, an upward movement of said handle will cause the bar 77 to tilt the arm 75 on its pivot, engage the collar 70, and thereby lift the rod 68 against the force of spring 71. The slots 78 in links 65 permit this upward movement of the handle to effect freeing of the bed 17 from engagement by the detent bar 68, so that said bed can be swung on the bearing means 18. The handle 62 can be released after a short swinging movement of the bed. The spring 71 will now be effective to press the rod into the seat 72, 73 or 74 next brought into register by continued swinging movement of the bed.

The guide member 27 comprises a casting 70 clamped on post 16 and formed with a guide opening 79 for the lower end of rod 68 to steady the same. The member 27 is, of course, oriented radially with the head 21.

The reticle means 28 is preferably carried by the member 27 to project radially outward of the

post 16. The means 28 comprises an arm 80 formed at its outer end with a frame 81 for optical means 82 and with a bracket 83 for engagement with the member 27. As shown, means 82 comprises vertically spaced lenses 84 and 85, the lower of which is provided with suitable cross hairs or markings in the form of a reticle 86 aiding the positional registering of the means 19 and 20. The arm 80 may be fixedly mounted or, as shown, means may be provided for vertically adjusting said arm to bring the lenses 84 and 85 to a desired optical spacing from either plate P or dial D. Accordingly, the bracket 83 is formed with vertically disposed slots 87 for bolts or screws 88 securing the arm 80 to the member 27. However, instead of the bolts directly clamping the arm in place, one or more springs 89 extending between pairs of screws 88 pass through holes 90 in said arm and bear against a wall of each hole to effect a frictional engagement between the springs 89 and the arm 80. The arm 80 is thereby adapted to be variably vertically positioned as desired.

In operation:

The printing plate P is placed on the block 40, engaged with the undercut pins 91, and held thereagainst by spring-tensioned clamp lever 92 carried by block 40. The dial D to be printed is pressed into place in the beeswax 53 of the block 52. The handle 62 is lifted to withdraw the rod 68 from detent engagement with the bed 17 and said bed is swung to bring the printing plate beneath the reticle means 28 as in Fig. 4. A selected engraving on the plate P is oriented with the reticle 86 by releasing the friction between block 40 and bed 17 and moving the block accordingly. The mentioned friction is then re-established. The same operation of orientation is carried out for the dial D by first swinging the bed to bring block 52 beneath the reticle and then moving the block to orient the dial with the reticle. Next, the printing plate is inked and excess ink removed from the surface of said plate. If the dial D to be imprinted has a lacquered surface, the tympan 23 is powdered with talc or French chalk to prevent sticking of the dial to the tympan. The bed is then again swung to register the printing plate, with the tympan, and the latter, by depressing the handle 62, is pressed against the inked printing plate to receive the ink from the engraving. The tympan is raised, the bed is swung to bring the dial D into register therewith, and the tympan is then again depressed to impress on the dial the imprint which it received from the printing plate.

When rod 68 is engaged in seat 74 as in Fig. 4, the reticle means and the printing plate are in register. When said rod is engaged in seat 73, the reticle means is in register with the dial and the tympan is in register with the printing plate. When said rod is in seat 72, the tympan is in register with the dial. The bed 17, therefore, has three positions; two for effecting orientation of the printing plate and dial by means of the reticle; one of said positions being used for effecting a transfer of ink from the printing plate to the tympan; and a third for registering the tympan and dial for imprinting the latter.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and

described, but desire to avail ourselves of all modifications that may fall within the scope of the appended claims.

Having thus described our invention, what we claim and desire to secure by Letters Patent is:

- 5 1. An offset printer comprising a fixed support, an adjustably movable bed on the support, a tympan carried by the support and movable toward and from the bed, spring means for normally holding the tympan away from the bed, manual handle means for moving said tympan toward the bed, a printing plate holder and a watch dial holder each individually and relatively adjustably carried by the bed, and detent means for holding the bed in adjusted position, said detent means comprising a spring pressed rod carried by the support and extending toward the bed, and selective seats in the bed for receiving one end of said rod, and means coupled with the handle means and engaged with the rod for moving said rod away from said seats upon movement of the handle means in a direction opposite to its movement when moving the tympan toward the bed.
- 10 2. In an offset printer a swingable bed having a plurality of seats, a support frame for the bed, a spring-urged detent rod carried by the frame and movable toward the bed for selective engagement in said seats, a tympan above the bed, handle means connected to the tympan and movable in one direction for moving said tympan toward the bed, and on operative connection between the handle means and the rod for moving the latter in a direction away from the seats upon movement of the handle means and the tympan away from the bed.
- 15 3. In an offset printer, a support frame, reticle means carried by said frame, a bed carried by the frame and movable relative thereto, at least two adjustable plate holders on said bed, and manually releasable means for frictionally holding the plate holders in adjusted position on the bed with respect to the reticle means.
- 20 4. In an offset printer, a movable member having an opening therethrough, a plate holder on the member and having a stem extending through the opening and movable laterally within the limits of said opening, a plate against the under face of said member and fixed to the stem, and spring-urged means carried by the member and exerting a pressure on the mentioned plate, and thereby creating a frictional force between the plate holder and the member.
- 25 5. In an offset printer, a movable member having an opening therethrough, a plate holder on the member and having a stem extending through the opening and movable laterally within the limits of said opening, a plate against the under face of said member and fixed to the stem, spring-urged means carried by the member and exerting a pressure on the mentioned plate and thereby creating a frictional force between the plate holder and the member, and a manual lever engaged with said pins for lifting the same and thereby releasing the mentioned frictional force.
- 30 6. An offset printer comprising a support, a bed swingably mounted on said support and having three seats therein, a first plate holder adjustably carried by the bed in general radial alignment with one of said seats, a second plate holder similarly carried by the bed in general alignment with another of said seats, optical means including a reticle fixedly carried by the frame and adapted 70 to guide the manual adjustment of the plates

on the bed and relative to each other, a tympan carried by the frame above the bed, handle means carried by the frame and engaged with the tympan to move the latter for impress engagement with plates on said holders, and ⁵ detent means including a rod connected to the handle means and movable together with the tympan into selective engagement in said seats to selectively and operatively align the optical means and the plate holders and the tympan and the plate holders.

7. An offset printer comprising a support, a bed swingably mounted on said support and having three seats therein, a first plate holder adjustably carried by the bed in general radial alignment with one of said seats, a second plate holder similarly carried by the bed in general alignment with another of said seats, optical means including a reticle fixedly carried by the frame and adapted to guide the manual adjustment of the plates on the bed and relative to each other, a tympan carried by the frame above the bed, handle means carried by the frame and engaged with the tympan to move the latter for impress engagement with plates on said holders, ¹⁵ ²⁰ ²⁵

detent means including a rod connected to the handle means and movable together with the tympan into selective engagement in said seats to selectively and operatively align the optical means and the plate holders and the tympan and the plate holders.
